UNITED STATES PATENT OFFICE.

DAVID STANLEY HAIR, OF MER ROUGE, LOUISIANA.

LUBRICANT-MEASURER.

1,201,287.

Specification of Letters Patent. Patented Oct. 17, 1916.

Application filed December 10, 1913. Serial No. 805,763.

To all whom it may concern:

Be it known that I, DAVID STANLEY HAIR, a citizen of the United States, residing at Mer Rouge, in the parish of Morehouse and State of Louisiana, have invented certain new and useful Improvements in Lubricant- Measurers, of which the following is a specification.

My invention relates to improvements in 10 lubricant measuring devices, being more especially associated with the delivery of heavy lubricants such as greases, etc.

Among other possible uses and features 15 may be mentioned the production of a mechanism that is portable, simple in operation, positive in action, economical to construct and provided with indicating means which show the quantity of grease delivered in gallon units, and fractional parts thereof or 20 on any other basis of measurement.

With these and related ends in view I 25 show such adaptations in the accompanying drawing as will disclose the broad features of my invention without limiting myself to the specific details shown.

Figure 1. shows a side elevation partly in section. Fig. 2. is an enlarged sectional elevation of the piston and its related valve parts. Fig. 3. is an elevation of the measuring dial. Fig. 4. shows the means for actuating the measuring hand. Fig. 5. is a plan view, disclosing the means used to move the piston up and down within the container.

A large container 1 is provided with a 35 cover 2 that may be suitably hinged thereto and also locked if desired. The bottom 3 of the container is conical. The whole is supported by legs 4 which in turn are secured to a base platform 46 that is fastened to suitable wheel supports 42 and 43. A handle 44, 40 is useful in moving the device from place to place.

A cylinder 6 is fastened to the conical part 3 by the flange 5. It projects upward into 45 the container 1 and also depends below the same, so as to approximately form an extension thereof. At its upper end a cap 7 is placed. It has a guide 8 and bearing 9 cast thereon. Suitable rivets or other fastenings 50 hold it in place.

10 is the operating shaft carrying a pinion 11 which meshes into rack 12 whose lower end is hollow and has a slot 14, flange 19 and threaded extension 20.

55 Between the head 7 and the lower end of the cone 3 rectangular openings 13 are made

in the cylinder 6 so as to form free communication with the grease stored in container 1 so that as the piston 21 is being raised the grease will flow through openings 13 into the space below the piston, passing through apertures 22 and between the annular space formed by the disk 17 and packing ring 23 held on piston 21. The disk 17 is secured to stem 15 by nut 18. The stem is 65 free to slide up and down in the lower end of rack bar 12 and a pin 16 sliding in slot 14 prevents disk 17 from rotating. The space below the piston fills with grease that is forced out on its downward stroke 70 through valve 25, nozzle 28 and delivery hose 29. The valve 25 is held in a raised position by spring 26. This spring has sufficient tension to withstand the weight of the grease above it and it serves to hold the 75 valve closed until the piston has passed the lower end of openings 13 when it opens to allow the fixed quantity of grease to be delivered. A casing 27 forms a delivery space below the valve and also serves as a seat for 80 the spring 26. In order that the delivery hose 29 may be kept from kinking, etc., as the device is moved from place to place a suitable hook 30 is secured to the side of the container. The cylinder 6 is closed at its 85 lower end by cap 24 which supports the valve 25 and casing 27. It is reinforced by tie rods 31 which connect it to the legs 4.

In order that the quantity of grease delivered may be measured I place a pinion 32 90 on shaft 10, exterior to the container 1. A gear 36 meshes therewith and a pointer 37 is connected with the gear through a short shaft 35. This shaft is held and the gears inclosed by a casing 33. That portion 34 of 95 the casing which covers gear 36 has formed thereon concentric price lines 40 which are intersected by radial quantity lines 39 and the pointer 37 has V shaped price leaders 38 which register with the concentric price circles. A thumb screw 41 may be used if desired to adjustably secure the pointer 37 to shaft 35. The shaft 10 is rotated back and forth by handle 45. The ratio of gear 36 to pinion 32 is such that an entire revolution of 100 the gear conforms to the entire stroke of piston 21. Approximately $\frac{1}{3}$ of the circumference of cover 34 is blank. This is the idle space passed over by the pointer 37 during the movement of piston 21 throughout the 110 length of slots 13 and the remaining $\frac{2}{3}$ of the circumference corresponds to the actual

delivery stroke of the piston. When the pointer is set at its proper place it may be permanently held by a suitable pin instead of set screw 41.

5 If desired the price values may be formed on a removable plate secured to the pointer 37 so that the circles 40 may be made to serve for varying values. In such cases the cover 34 would also have a removable plate 10 held by screws 47 on which the radial lines 39 and circles 40 as well as the resultant prices for varying quantities at different prices would be indicated so as to conform to the price values on the pointer or marked at 15 the termination of the concentric circles. In order to facilitate the changing of plate 34 without removing the pointer 37 from the shaft 35 a slot of sufficient width to pass shaft 35 may be formed in such plate, projecting radially from its center into the unoccupied space, as shown by dotted lines 48 of Fig. 3. In this way the device is easily 20 changed from one set of values or units of measurement to others as desired. In order 25 to make the "unit" space below the piston conform to the indications on plate 34 the length of the packing ring 23 may be changed as shown in Fig. 2 according to the basis of values or quantities that are to 30 be used. The "vacant" space on plate 34 would obviously conform to such change.

The action of the device is as follows: On the down stroke of the piston all the imprisoned grease is forced out ahead of it but 35 the lubricant also follows after the piston so that the moment it starts to rise the disk 17 and stem 15 remain stationary until slot 14 engages pin 16, when the disk 17 is raised with the piston, at which time the grease 40 flows between 17 and 23 into the "unit" 45 space below the piston, continuing to do so as long as the piston is rising. On the down stroke, the surplus material which has entered cylinder 6 is forced out through openings 13, disk 17 remaining within the packing ring 23 so as to keep openings 22 closed.

In case it should be desired to operate the measurer by power suitable automatic reversing devices, of well known construction 50 could be used to control the timing and the direction of movement of the piston.

What I claim is—

1. In measuring devices, a storage container, a measuring and delivery cylinder 55 connected therewith, a piston slideable in the latter, means for moving the piston to and fro, an axially projecting packing ring thereon, an independently movable head to said piston, means for automatically actuating the same, and a suitable delivery pipe having a self-closing exit valve placed therein.

2. A storage container, a measuring chamber in connection therewith, the latter projecting into the former, suitable openings 60 leading from one to the other, a removable

head supported by the upper end of the measuring chamber, a slideable piston operable within said chamber, means for actuating the same secured to the head, a flexible axial extension to the piston, openings in the piston, an independently movable head co-operating with the extension and adapted to be actuated in advance of the piston, and suitable means for controllably delivering the contents of the measuring chamber. 70

3. A portable container, a measuring chamber connected therewith, a combined measuring and delivery piston sliding in said chamber, an axially projecting packing secured to the piston, openings in the piston, a separately movable head slideable adjacent to said packing, and automatic means for controlling the inlet and outlet to said chamber through the movement of the piston. 75

4. A storage container, a cylinder connected therewith, a piston slideable in the cylinder, a packing member projecting from the piston, a movable head to the piston adapted to coact with the said packing, and a suitable delivery outlet controlled by the 80 movement of the piston. 85

5. A storage container, a delivery chamber connected therewith, a displacing piston slideable therein, means for actuating the same, an independently and automatically movable head supported by the piston, a suitable axially projecting packing member 95 coacting with the piston, the delivery chamber and the independent head, and means for controlling the free exit from the chamber. 100

6. A suitable container comprising a storage chamber, a delivery chamber connected therewith, a piston operable in the latter, an axially projecting packing secured thereon, an independently movable head supported by the piston, suitable passage ways in the piston, the same being controlled through the automatic movement of the independent head in co-operation with the packing, and 105 an outlet formed in said delivery chamber. 110

7. A measuring chamber of unit capacity, a plunger movable therein, a removable extension projecting from the plunger into said chamber, an independently movable head supported by the plunger adapted to co-act with such extension to vary the capacity of the chamber, means for delivering the contents of the chamber through a movement of the plunger, and adjustable indicating means operated thereby the same being co-ordinated with the capacity of the measuring chamber. 115

8. A suitable measuring device, comprising a storage container, a measuring cylinder of unit capacity connected therewith, a delivery device operable therein, removable extensions therefor adapted to vary the capacity of the cylinder, and indicating mechanism connected to the delivery device, com- 125 130

- prising an interchangeable member showing the relation of prices to quantities in coordination with the means for varying the capacity of the measuring device.
- 5 9. A suitable container, a conical bottom thereon, a delivery cylinder secured thereto, openings leading from the cylinder to the container, a piston slideable in said cylinder, means for actuating the piston, openings in 10 the piston, means for automatically closing and opening the same, a delivery pipe, an automatic valve between the pipe and cylinder, and a suitable quantity and price indicating device connected thereto.
- 15 10. A suitable measuring device comprising a storage chamber having a conical bottom, a measuring chamber projecting into the storage chamber, openings in its walls,
- an outlet at its bottom end, a piston slideable therein, openings therethrough, a hollow stem 20 secured thereon, a slot in such stem, a rod slideable within the stem, a head secured thereto in advance of the piston, a pin on the rod adapted to engage the slot, an extension to the stem, teeth formed thereon, a pinion 25 meshing with the teeth, and means for rotating the pinion so as to move the stem and extension to and fro whereby the head is carried with the piston under the control of the slot formed in the stem. 30

In testimony whereof I affix my signature in presence of two witnesses.

DAVID STANLEY HAIR.
